US0D1109656S

(12) **United States Design Patent** (10) **Patent No.:** **US D1,109,656 S**
(45) **Date of Patent:** **** Jan. 20, 2026**

(54) **POWER CONTROL UNIT**

(71) Applicant: **GUANGDONG EPROPULSION TECHNOLOGY LIMITED**,
Dongguan (CN)

(72) Inventors: **Youquan Yuan**, Dongguan (CN);
Yuefeng Liu, Dongguan (CN); **Weifu Yuan**, Dongguan (CN)

(73) Assignee: **GUANGDONG EPROPULSION TECHNOLOGY LIMITED**,
Dongguan (CN)

(**) Term: **15 Years**

(21) Appl. No.: **29/960,771**

(22) Filed: **Sep. 2, 2024**

Related U.S. Application Data

(62) Division of application No. 35/519,970, filed on Feb. 8, 2023 (U.S. filing date under 35 U.S.C. 384), and having an international filing date of Feb. 8, 2023, now Pat. No. Des. 1,062,560.

CLAIM

The ornamental design for a power control unit as shown and described.

DESCRIPTION

FIG. 1 is a front, right and top perspective view of a power control unit, showing our new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the power control unit that form no part of the claimed design.

1 Claim, 8 Drawing Sheets
